(57) **CLAIM**

The ornamental design for a delivery robot, as shown and described.

DESCRIPTION

The patent or application file contains at least one drawing executed in color. Copies of this patent or patent application publication with color drawing(s) will be provided by the Office upon request and payment of the necessary fee.

1. Delivery robot
2. Delivery robot
3. Delivery robot
- 1.1 : Front
- 1.2 : Back
- 1.3 : Left
- 1.4 : Right
- 1.5 : Top
- 1.6 : first perspective
- 1.7 : second perspective

- 2.1 : Front
- 2.2 : Back
- 2.3 : Left
- 2.4 : Right
- 2.5 : Top
- 2.6 : first perspective
- 2.7 : second perspective
- 3.1 : Front
- 3.2 : Back
- 3.3 : Left
- 3.4 : Right
- 3.5 : Top
- 3.6 : first perspective
- 3.7 : second perspective
- 3.8 : front view in a varied state of use
- 3.9 : back view in a varied state of use
- 3.10 : left view in a varied state of use
- 3.11 : right view in a varied state of use
- 3.12 : top view in a varied state of
- 3.13 : first perspective view in a varied state of use
- 3.14 : second perspective view in a varied state of use

Colors shown in designs 2 and 3 form a part of the claimed designs; the light orange color indicated in reproductions 3.1 and 3.6 means that the revolving door of the delivery robot

(Continued)

is in a closed state; the dark orange color indicated in reproductions 3.8 and 3.13 show a varied state of use where the revolving door of the delivery robot is in an open state.
